US0D1041795S

(12) **United States Design Patent** (10) **Patent No.:** **US D1,041,795 S**
(45) **Date of Patent:** **** Sep. 17, 2024**

(54) **POSTURE GARMENT**

(71) Applicant: **INFINIA FORMA, LLC**, New York, NY (US)

(72) Inventors: **Jaclyn L. Jirsa**, New York, NY (US); **Roy Prosise**, Cedar Park, TX (US)

(73) Assignee: **INFINIA FORMA, LLC**, New York, NY (US)

(**) Term: **15 Years**

(21) Appl. No.: **29/820,763**

(22) Filed: **Dec. 23, 2021**

Related U.S. Application Data

(62) Division of application No. 29/718,420, filed on Dec. 24, 2019, now Pat. No. Des. 953,691.

(57)

CLAIM

The ornamental design for a posture garment, as shown and described.

DESCRIPTION

FIG. 1 is a front view of a posture garment, showing the new design.

FIG. 2 is a side view of the posture garment of FIG. 1; and,

FIG. 3 is an end view of the posture garment of FIG. 1.

The dashed lines depict portions of the posture garment that form no part of the claimed design.

1 Claim, 1 Drawing Sheet
